UNITED STATES PATENT OFFICE

FRED N. J. OHLSON, OF PIERSON, FLORIDA

BALL GAME APPARATUS

Application filed June 27, 1928. Serial No. 288,668.

This invention relates to game apparatus wherein balls are adapted to be thrown to displace panels in order to disclose numerals or data which may be used in computing the score.

An important object is to provide a novel construction wherein the figures, numerals or the like used for computing the score, and their arrangement, may be varied.

10 A further prime object is to provide a novel construction wherein a novel inclined floor is used in connection with a conveyor for returning balls after being thrown, automatically to the starting box or receptacle.

15 A further important object is to provide a novel construction of means whereby the displaceable panels may be reset, and to provide novel escapement and control means for the movable sign or element which displays 20 the figures or the like for computing the score.

Various additional objects and advantages will either be pointed out or become apparent 25 from a consideration of the description following taken in connection with accompanying drawings illustrating one operative embodiment.

In said drawings:

Figure 1 is a side view in elevation of the 30 improved base ball game apparatus some of the parts being shown broken away.

Figure 2 is a horizontal sectional view on the plane indicated by the line 2-2 of Figure 1.

35 Figure 3 is a longitudinal sectional view on the vertical plane indicated by the line 3-3 of Figure 2.

Figure 4 is a plan view showing the operating mechanism for replacing the target and 40 for operating the adjustable score sheet.

Figures 5 and 6 are transverse sectional views on the planes indicated by the line 5-5, and 6-6, respectively, of Figure 3, and

45 Figure 7 is a detail view of the operating mechanism for the reel controlling the position of the score sheet.

Referring specifically to the drawings, the device may comprise a housing or cage-like structure which is generally designated 10 50 and which may be permanently built into a

building or be portable or knock down so that it may be transferred from place to place according to the field of use.

The cage 10 has frame members as at 11 to which wire netting, grating or the like as 55 at 12 is fastened at the top and both sides, the cage being open at the upper portion of the rear as at 13, so that balls may be thrown forwardly. The base of the structure is shown at 14 and at a distance above the same, suitably supported in the frame 10 is a rearwardly and downwardly inclined shelf 15 which leads to a trough 16 directly at the base of the opening 13 and which is adapted to contain baseballs or other balls which are thrown 60 in the playing of the game.

At the forward end of the housing or cage 10 is a suitable skeleton frame 17, providing a multiplicity of relatively closely arranged rectangular or square openings 18, each of 70 which has a displaceable panel 19 disposed therein. Such panels 19 each have a suitable design or emblem painted or delineated thereon as shown and each is fastened rigidly to a hinge or pintle rod 20, pivotally mounted in adjacent parts of the frame 17, whereby said panels 19 are pivoted on a horizontal axis adjacent their bases. The panels 19 will normally remain elevated or they may be arranged to incline slightly upwardly and rearwardly.

When the balls are thrown forward, if they strike any panel 19, the same will be displaced, falling rearwardly and downwardly, permitting the ball to travel through the 85 corresponding space 18 and strike a score sheet or back stop sheet 21 and 22, respectively.

Said frame 10 includes uprights 23 in the rear of frame 17 in the upper portions of 90 which a roller 24 is journaled by means of trunnions 25. The score sheet 21 may be of canvas or other flexible material and is adapted to hang over the roller 24, the forward end of the sheet 21 having a bar 26 95 fastened thereto which serves as a weight.

The back stop sheet 22 is stationarily fastened to the uprights 23 and may be of any desired material, for instance canvas or even wood or metal as desired. Each of the 100

sheets 21 and 22 is divided up into spaces 27 corresponding in number and size to the openings 18 and each space having a score numeral or indication 28 painted or otherwise delineated thereon. The spaces 27 are adapted to register with the said openings 18. Thus it will be realized that when the panels 19 are displaced, numerals on the sheets 21 and 22 in front thereof will be disclosed and after the requisite number of balls allowed per person per game have been thrown, the numerals in the spaces 27 may be added to give the score or any other rule or rules for playing the game may be utilized, it being obvious that many modifications thereof are permissible and specifically form no part of the present invention.

Pivoted to the frame 17 as at 29 are generally U-shaped frames 30 having horizontal bars 31 against which the panels 19 rest when displaced or lowered. The frames 30 are connected together by flexible elements or cords 32 and longer cords or flexible elements 33 pass from the uppermost one, and are trained over suitable guide pulleys 34 of the frame 17 or adjacent the same and are then connected to a master cable or flexible element 35 leading from a hand operable lever 36 which is pivoted as at 37 to a base 38 fastened on the base 14. The weight of the lifting frames 30 normally holds them in their lowered position so that after the lever 36 is pulled rearwardly to restore the panels 19 to closed position, the frames 30 will automatically by gravity fall in normal position where they rest on elements 39 connecting frame 17 and uprights 23.

The sheet 21 at its lower edge has cables or flexible elements 40 connected thereto which are trained over guide pulleys 41 each fastened to suitable parts of the housing 10, and are then secured to a master cable or flexible element 42 which is fastened to a drum 43 and adapted to be wound around the same. Such drum is loose on a shaft 44 suitably mounted in a frame 45 supported on the base 14. Rigid with the drum 43 is a ratchet wheel 46, also loose on shaft 44. A detent 47 normally holds the ratchet wheel 46 and pulls 48 against retrograde movement, being urged into engagement with the ratchet by an expansive spring as at 48, and being pivoted as at 49 to the frame 45. Also loosely pivoted on the shaft 44 is a lever 50 to which a bar 51 is pivoted and which in turn is pivoted to an operating lever 52 pivoted as at 53 to the base 38. A contractile spring 54 is fastened to lever 52 and frame 45 and serves to urge the lever 52 to its foremost position. Pivoted to the lever 50 as at 55 is a hook pawl 56 having a lug 57 thereon and a tooth 58, extending from opposite sides. A contractile spring 59 is connected both to the pawl 56 and the lever 50 tending to urge the pawl 56 into engagement with the ratchet wheel so

that when the lever 52 is pulled rearwardly, the ratchet wheel will be moved one tooth which corresponds to the height of a space 27 so that according to each manipulation of the lever 52 in the manner aforesaid, the score sheet 21 will be pulled down a distance corresponding to the height of a space 27, against the weight of the bar 26. In this way, since the sheets 21 and 22 are of the same size and the numerals thereon are different, preferably being reversed from top to bottom, the scoring values of the hits made by the ball may be changed from time to time by moving the score sheet 21 relatively to the score sheet 22 to vary the numerals exposed by displacing one or more of the panels 19. It will be apparent that as the spaces 27 on sheet 21 have the scoring numerals 28 differently arranged from those on sheet 22 that a different score would result by displacing one or more panels 19 if sheet 22 is entirely exposed from that that would result if sheet 21 entirely covers sheet 22, and that by arranging sheet 21 to expose one or more of the horizontal rows of spaces 27 of sheet 22 a different score would result for each change of position of the sheet 21. For example, in the construction shown in the drawings, it is possible to have five variations of the scoring values of the spaces of the combined score sheets. Normally the hook 56 is disengaged from the ratchet wheel by the abutment or resting of lug 57 on an abutment 60 provided on the frame 45 adjacent to the same.

In order to release the ratchet and drum so that the weight 26 will move the sheet 21 to its uppermost position, another operating lever 62 is provided, being pivoted at 63 to the plate 38 and being urged forwardly by a contractile spring 64 fastened to the lever and to the frame 45. Such lever 62 has a lug 65 arranged in engagement with a lever 66 pivoted at 67 to a bracket 68 on the base 14. Lever 66 engages one end of the detent 47. Hence rearward movement of the lever 62 causes lug 65 to tilt lever 66 and thereby depress the rear end of detent 47 out of engagement with the ratchet wheel 46, whereupon the weight 26 will cause the sheet 21 to move to its highest position at the rear portions thereof, accordingly drawing on the cables 40 and 41 and turning the drum 43 and ratchet wheel 46.

In order that the apparatus may be well illuminated, electric lamps may be provided adjacent the opening 13 as at 69 and a row of lamps may be provided as at 70 between the frame 17 and the sheet 21, being supported for instance on a frame 71 and being protected from contact by the thrown balls by grating or metal fabric as at 72. Such lamps may be of any capacity or style desired but may be particularly headlights of the type used on automobiles.

The levers 36, 52 and 62 extend upwardly

through and above slots 73, 74 and 75 provided in the shelf 15 and which slots are of a length to limit the throw of such levers.

Extending forwardly from the shelf 15 are shelves or platforms 76 which incline downwardly and forwardly from the platform 15 to the frame 17 and also incline especially at their forward ends downwardly and inwardly. By reason of such inclination of the platforms 76, thrown balls fall into or roll into a longitudinal central opening 77 which is extended also part way through the shelf or platform 15. In such slot or opening 77, an endless conveyor 78 operates so as to return the baseballs to the pocket or box 16. The conveyor 78 may be of any approved type, having flights 79 thereon to assist in moving the balls.

The conveyor 78 is trained over pulleys 80 suitably mounted on frame 17 and on a frame 81. A tensioning roller 82 may be operatively associated with the conveyor 78. A motor, such as an electric motor 83 is mounted on the base 14 and drives a belt 84 which in turn drives a pulley 85 journaled as at 86 on the frame 91 and having a pulley 87 rigid therewith over which another belt 88 passes which is trained over a pulley 89 on the adjacent roller 80. A tensioning roller 90 may be associated with the belt 84. Thus it will be realized, the conveyor 78 is kept constantly in motion when the electric current is passing through the motor 83, to return the balls to the box 16.

Various changes may be resorted to provided they fall within the spirit and scope of the invention.

I claim as my invention:

1. Game apparatus having a shelf, a receptacle to which the same leads and adapted to hold balls, platforms extending forwardly and downwardly from said shelf, a conveyor to return balls onto said shelf so as to roll into the receptacle, and said platforms being inclined inwardly and downwardly to cause the balls to roll onto the conveyor.

2. Game apparatus of the class described having a plurality of members containing score data, and means to vary the position of one member with respect to the other so as to alter the arrangement of the score data.

3. Game apparatus of the class described having a stationary sheet containing score data, and a movable sheet containing score data and coacting therewith.

4. Game apparatus of the class described having a stationary sheet containing score data, a movable sheet containing score data and coacting therewith, a roller over which the movable sheet passes, and means weighting one end of said movable sheet.

5. Game apparatus of the class described comprising uprights, a stationary score sheet carried by said uprights, a roller supported by said uprights, a movable score sheet

trained over said roller, means engageable with the movable score sheet to pull the same in one direction, and means to urge movement of the score sheet in the other direction.

6. Game apparatus having a frame provided with openings through which articles are adapted to be projected, relatively movable score members in the rear of said openings and adapted to register therewith, the relative movement of the members permitting variation in the score data exposed. 70

7. Game apparatus having a frame provided with openings through which articles are adapted to be projected, relatively movable score members in the rear of said openings and adapted to register therewith, and means operable to move the movable score sheet distances corresponding to the height of said openings. 80

In testimony whereof I affix my signature. 85
